KITCHEN KNIFE

Junior C. Poirier, Duluth, Minn.

Application April 7, 1949, Serial No. 1,858

Term of patent 14 years

(Cl. D22—3)

To all whom it may concern:

Be it known that I, Junior C. Poirier, a citizen of the United States, residing at Duluth, in the county of St. Louis and State of Minnesota, have invented a new, original, and ornamental Design for a Kitchen Knife, of which the following is a specification, reference being had to the accompanying drawing, forming part thereof.

In the drawing:

Fig. 1 is a side elevational view of a kitchen knife showing my new design;

Fig. 2 is a sectional view on the line 2—2, Fig. 1.

Fig. 3 is a sectional view on the line 3—3, Fig. 1.

Fig. 4 is a sectional view on the line 4—4, Fig. 1.

The essential features of the design reside in those portions shown in full lines.

I claim:

The ornamental design for a kitchen knife, as shown and described.

JUNIOR C. POIRIER.
